US00D608301S

(12) **United States Design Patent**
Clark et al.

(10) **Patent No.:** US D608,301 S
(45) **Date of Patent:** ** Jan. 19, 2010

(54) **IRRIGATION CONTROLLER CONTROL PANEL**

(75) Inventors: **Donald B. Clark**, Carlsbad, CA (US); **Roger S. Neitzel**, Escondido, CA (US); **Robert Jenkins**, San Diego, CA (US); **Charles Curbbun**, Leucadia, CA (US); **Andrew Zoolakis**, Carlsbad, CA (US); **Bill Leach**, Oakdale, CA (US)

(73) Assignee: **Rain Bird Corporation**, Azusa, CA (US)

(**) Term: **14 Years**

(21) Appl. No.: **29/337,331**

(22) Filed: **May 19, 2009**

(51) **LOC (9) Cl.** **13-03**

(52) **U.S. Cl.** **D13/162**

(57) **CLAIM**

We claim the ornamental design for an irrigation controller control panel, as shown and described.

DESCRIPTION

FIG. 1 is a rear view of an irrigation controller control panel showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken line portion of the figures is included to show the unclaimed subject matter only and forms no part of the claimed design.

1 Claim, 4 Drawing Sheets
